RAZOR BLADE SHARPENER

Vaclav F. Stegner, Racine, Wis.

Application November 17, 1949, Serial No. 127,952

1 Claim. (Cl. 51—86) *

1

My invention appertains to razor blade sharpeners and more particularly to a novel machine for sharpening double-edged razor blades. The blade holder embodies a clamping rod adapted to be oscillated back and forth by a lever secured to one end of said clamping rod and engaging a double faced circular cam, whereby the edges of the blade are alternately forced against the diagonally positioned upper and lower abrading cylinders to automatically sharpen the blade edges. The double faced circular cam is provided with a spring controlled gate which is moved back and forth across a throat that communicates with the outer and inner circular cam tracks, whereby said clamping rod and its holding tongue are oscillated, the cam being mounted upon the shaft of one of the cylinders to be designated as the master cylinder, the shaft of which master cylinder is manually rotated by a crank.

A further object of my invention is to provide hinged housing sections for the pairs of cylinders, each of said housings being provided with brackets which serve as bearings for the shafts of the abrasive cylinders, the said housing sections being folded one upon the other and locked in their folded position when a blade sharpening operation is affected.

With the above and other objects in view, which will appear as the description proceeds, the invention resides in the novel construction, combination and arrangement of parts, substantially as hereinafter described, and more particularly defined by the appended claim, it being understood that such changes in the precise embodiment of the herein disclosed invention may be made as come within the scope of the claim.

In the accompanying drawings is illustrated one complete example of the physical embodiment of the present invention constructed according to the best mode so far devised for the practical application of the principles thereof.

In the drawings:

Figure 1 represents a sectional elevation of a razor blade sharpener embodying the features of my invention, the section being indicated by line 1, 1 of Figure 2.

Figure 2 is a top plan view of the same.

Figure 3 is a cross section through one of the housing sections, the section being indicated by line 3, 3 of Figure 2.

Figure 4 is an enlarged fragmentary sectional view through one of the sets of abrasive cylinders, the section being indicated by line 4, 4 of Figure 2.

2

Figure 5 is a fragmentary side elevation of the pairs of cylinders illustrated in Figure 4.

Figure 6 is a similar view particularly illustrating the shifts from the lower cam groove to the upper cam groove through control of a spring actuated gate.

Figure 7 is a detailed cross sectional view through the circular cam and associated parts, the section being indicated by line 7, 7 of Figure 4.

Figure 8 is a sectional face view of the cam and blade carrying clamping rod form illustrated, its actuating lever riding upon the outer cam face, the section being indicated by line 8, 8 of Figure 7; and

Figure 9 is a face view of the rotatable blade locking tongue.

Referring by characters to the drawings, 1 and 1' indicate sections of a housing which are connected by a hinge 2, the said housing sections when folded one upon the other, as indicated in dotted lines, Figure 1, are suitably secured by a pin 3 and pivoted latch member 4 mounted upon the housing sections.

Each housing section has fitted therein oppositely disposed bearing brackets 5 and 5', as clearly illustrated in Figure 2 of the drawings.

The lower housing section 1 has journaled in the bearing brackets companion shafts 6, 6', which shafts and hubs 7 have fitted thereto rubber abrasive cylinders 8, 8'. The opposite hinge section of the housing being provided with shafts 9, 9 carrying hubs 10, 10 that are fitted with rubber cylinders 11. At one end of the cylinder shafts 9, 9 and 6, 6', the same have secured thereto meshed gear wheels 11', 11'' and 11'', 11''', respectively, whereby upon closing of the housing sections, the two pairs of gear connected abrasive cylinders are intermeshed, it being understood that the bottom cylinder 8, for identification, is termed a master cylinder, the shaft 6 of which extends through the housing section and carries an actuating crank 12, whereby power is applied to the master cylinder and the associated cylinders, through the gear train.

The shaft 6 of the master cylinder has secured thereto a circular cam 13, having an outer cam face 13' and an inner cam face 13''. The cam faces are interrupted to form a communicating throat 14 between the same. The throat 14 is controlled by a gate 15, which gate is pivoted to the circular cam and is controlled by a coil spring 16, whereby said gate is held in one position across the surface of the inner cam face

13", as best shown in Figures 4 and 6 of the drawings.

The housing brackets 5' are provided with centrally disposed projecting necks 5", which necks serve as bearings for a mutilated clamping rod 17, the said rod being pivotally mounted centrally of the two pairs of abrading cylinders when the same are folded in their working position.

The clamping rod 17 is provided with a flat surface 18, having a central aperture 18' therein, and adjacent the ends of the clamping rod, it has extending outwardly therefrom oppositely disposed lips 19, and adjacent said lips, the clamping rod surface 18 has projecting upwardly therefrom on the flat surface, a pair of pins 20.

Pivotedly mounted upon the flat surface 18 of the clamping rod is a tongue 21, having a shank 21' that is in engagement with the central aperture 18'.

The ends of the tongue 21 are in locked engagement with the lips 19 and adjacent said ends, the lower face of the tongue is formed with channels 20' for clearing the pins 20.

Also secured to one end of the clamping rod is a rocking lever 22 having a roller 22' at its free end, which roller is adapted to ride upon the inner or outer circular cam faces 13', 13", whereby the rod 17 is oscillated back and forth. The end of the lever 22 is connected to a coil spring 23, the opposite end of which spring is secured to a finger 23' that extends from one of the brackets 5', as indicated in Figures 4 to 6 inclusive.

From the foregoing description, when it is desired to sharpen a double edge razor blade 24, the tongue 21 being removed, said razor blade is inserted over the flat surface of the clamping rod and apertures in the blade are engaged by the pins 20.

Thereafter, the clamping tongue is adjusted in its position upon the clamping rod 21 and the same is swung about its pivot stud, whereby its ends engage the under faces of the lips 19 and the channels 20' of the tongue travel over said pins, whereby the blade is securely locked to the clamping rod.

Thereafter the upper section 1' of the housing is swung to its locked position, whereby the four cylinders are in meshed engagement through their interlocking gear wheels and the housing sections being locked together; all that is necessary to sharpen the blade is to rotate the cranked master cylinder 8, whereby all of the abrading cylinders are put into motion and at the same time the right hand lower edge of the blade is pressed against the abrasive cylinder 8', while the left hand upper edge of the blade is pressed against the upper left hand abrasive cylinder, as indicated in dotted lines, Figure 1.

In this position, the roller 22' of the lever 22 will make a complete revolution upon the outer cam face 13' and when said roller reaches the throat 14, the spring pressure upon its lever will cause the roller to drop down into the throat and make a second complete turn, whereby the left hand lower edge of the blade is sharpened upon its face, while the right hand upper edge is sharpened upon the opposite face. When this complete revolution of the roller is affected, said roller will engage the gate 15, as shown in Figure 6, whereby the roller is deflected upwardly

by the gate to again engage the outer cam face 13', thus it will be noted that oscillation of the blade is affected, due to the lever roller which will alternately drop through the throat from the outer cam surface to the inner cam surface and thereafter be lifted from said inner cam surface to the outer cam surface, in a complete revolution, whereby oscillation of the blade is affected to sharpen the lower beveled edge and the upper beveled edge when the blade engages the master cylinder, and an obliquely disposed upper cylinder while the opposite bevels will also be ground as they engage the surfaces of the oppositely disposed oblique abrading cylinders.

I claim:

A sharpener for double-edge razor blades comprising housing sections in pivotal connection and adapted to close one over the other, a pair of bearing brackets carried by each housing section, a pair of equally spaced longitudinal shafts journaled in each pair of bearing brackets respectively, abrasive cylinders mounted on said shafts, said shafts being geared for synchronous rotation when the housing sections are closed one over the other, a crank splined to one of said shafts whereby said associated abrading cylinder is a master cylinder, a cam secured on one end of said master cylinder and adapted to rotate therewith, said cam having an outer circular face and an inner circular face and a throat opening formed in said outer cam face in open communication with said inner cam face, a transversely extending gate pivoted at one end to the inner cam face and having its other end terminating adjacent the upper surface of the outer face, said pivoted gate adapted to move across said throat opening in the outer cam face, a spring secured to said gate adapted to resiliently urge said gate against one end of the throat opening, a longitudinal clamping rod journaled in one pair of said brackets centrally between said abrasive cylinders, means on said clamping rod for detachably holding a double-edge blade, a lever having one end secured to the clamping rod and its other end resiliently secured to said bracket, and a roller mounted on said lever intermediate its ends for alternately engaging said cam faces, whereby upon rotation of the cam, said roller will be urged into the open throat and onto the inner cam face to engage said pivoted gate and move said gate against spring tension to the opposite end of the throat opening to guide said roller through the throat opening and onto the outer circular cam face, thereby causing the cutting edges of the blade to alternately engage the pairs of diagonally disposed abrading cylinders.
